RECIPROCATING CONVEYER

Donald C. Campion, Detroit, Mich., assignor to
Loftus Engineering Corporation, Pittsburgh,
Pa., a corporation of Maryland

Application November 21, 1944, Serial No. 564,477

19 Claims. (Cl. 198—220)

1

This invention relates to a shuffle conveyor. It is the object of this invention to produce a shuffle conveyor which is efficient and economical in operation.

The invention contemplates in particular a conveyor that is adaptable for many uses and which will handle or convey a wide diversity of parts ranging from paper clips to heavy forgings.

Another advantage of my conveyor is that when the conveyor is used, e. g., with a heat treating furnace, the driving parts can be positioned without the furnace and away from the furnace heat so that they will not get hot.

My invention also contemplates a shuffle conveyor whose speed can be accurately timed and varied over an extremely wide range.

Fig. 1 of the drawing shows my shuffle conveyor with the compressed air circuit for operating the same and the electrical circuit for timing and controlling the operation of the conveyor.

Fig. 2 shows a modified form of my shuffle conveyor.

My conveyor comprises a conveyor pan 1 which can conveniently be a sheet metal trough into which the work to be conveyed is lowered. The pan 1 is supported upon bracket 2 which is fixed to piston rod 3. Rod 3 is fixed to piston 4 within cylinder 5. Piston rod 6 is fixed to piston 7 in cylinder 6. Bracket 2 is connected with bracket 12 fixed to cylinder 6 by means of a toggle lever comprising links 9 and 10. Link 10 is pivoted on bracket 2 as at 11. Link 9 is pivoted on stationary support 12 as at 13. Links 9 and 10 are pivotally connected together as at 14. Link 9 is in the form of a bell crank lever having a depending leg 15.

Compressed air under high pressure is supplied to cylinder 5 through lines 16, 17 and 18. Line 18 is connected to a source of compressed air under pressure (not shown). Line 18 is also connected to cylinder 5 through line 19, expansion chamber 20 and line 21. A pressure reducing valve 22 in line 21 reduces the pressure of compressed air from line 18 as it enters the expansion chamber. Cylinder 6 is connected with compressed air line 18 through lines 17 and 23. Cylinder 6 is also connected by line 24 with the low pressure air in expansion chamber 20. Valve 25, controlled by solenoid 26, controls communication between lines 16 and 17. Valve 27, controlled by solenoid 28, controls communication between lines 17 and 23. Lines 29 and 30 are exhaust lines which are also controlled respectively by valves 27 and 25. A pressure controlled

2

switch 31 is connected into line 32 which is connected to line 16.

The timing of the conveyor is controlled by a time delay relay 33 which is arranged to open and close switch 34 at regular timed intervals. The time interval between the opening and closing of switch 34 can be varied. For illustrative purposes the time delay relay comprises a switch 34 controlled by a solenoid 35, a flexible diaphragm 36 connected by rod 37 to switch 34. Diaphragm 36 is mounted in a closed housing 38 which has a variable air bleed orifice 39 at atmosphere. A compression spring (not shown) within housing 38 normally biases switch 34 to open position. It is, of course, understood that any suitable conventional time delay relay can be used for timing the cycle of operation of my shuffle conveyor.

The operation of my shuffle conveyor is as follows: As stated above, the parts which are to be conveyed through a heat treating furnace or along the course desired are dumped into the left hand end of conveyor pan 1. Pan 1 is a reciprocating pan and is at the end of its right hand or forward stroke. The operator closes switch 40 in the 110 volt line circuit. After switch 40 is closed the operation of my shuffle conveyor is entirely automatic. Limit switch 41 has been closed by tripping member 42 when the conveyor pan 1 reached the end of its forward stroke and switch 41 remains closed until it is opened by member 42 when pan 1 reaches the end of its backward stroke. With switch 41 closed, current flows through the 110 volt circuit comprising line 43, switch 41, line 44, solenoid 35, line 45, switch 40 and line 46. Solenoid 35 being energized closes switch 34 so that we now have current established in a circuit comprising line 47, switch 34, line 48, solenoid 26, line 49, line 44, switch 41 and line 43. Solenoid 26 being energized, valve 25 is moved to the position shown to connect lines 16 and 17 so that air under high pressure flows into the right hand end of cylinder 5. However, toggle 9, 10 is in made position 45 so that piston 4 does not move but remains in the position shown until the air pressure builds up in line 32 to close pressure actuated switch 31.

Switch 31 can be set to close at whatever pressure desired up to the pressure existing in high pressure line 18. When switch 31 closes, then current flows in a circuit comprising line 43, switch 41, line 44, line 50, switch 31, line 51, solenoid 28, line 52, switch 40, line 46. This energizes solenoid 28 so that valve 27 is shifted upwardly from the position shown to connect

lines 17 and 23. As the pressure rises in cylinder 6 to the left of piston 7, piston 7 moves to the right and acts through rod 8 and leg 15 of the toggle to break the toggle lever 9, 10, thereby permitting the air under high pressure in cylinder 5 to shift pan 1 to the left. Due to the high pressure existing in cylinder 5 to the right of piston 4, as soon as toggle 9, 10 is broken the air cylinder actually jerks pan 1 to the left from under the work and the inertia of the work holds it in its position. The inertia of the work overcomes the friction between the work and pan 1 so that the work remains nearly stationary as the pan is jerked back. The low pressure air in cylinder 5 on the left hand side of piston 4 serves as a cushion for piston 4 at the end of the quick rearward stroke or jerk of pan 1 brought about by the action on piston 4 of the air under high compression in the right hand end of cylinder 5. As soon as, or preferably slightly before, pan 1 reaches the end of its rearward or leftward stroke, switch 41 is broken. This deenergizes solenoids 35, 26 and 23 thereby causing the time delay relay 33 to immediately open switch 34. When solenoids 26 and 23 are deenergized, lines 16 and 23 are connected with their respective exhaust lines 30 and 29, exhausting the high pressure air from cylinders 5 and 6. The low pressure air in lines 18 and 24 now slowly moves or retracts piston 7 toward the left to retract rod 8 and slowly moves piston 4 toward the right which through rod 3 and bracket 2 slides pan 1 slowly forward or to the right in the direction of flow, as indicated by the arrow, carrying the load or work with it. As soon as pan 1 reaches the end of its forward or rightward stroke, switch 41 closes thereby again energizing solenoid 35 which will close switch 34 immediately if air bleed 39 is wide open or which will close switch 34 after a time delay sufficient to permit the air to be bled from housing 38 through air bleed orifice 39 and the cycle above described repeats itself.

It is, of course, understood that as soon as line 16 is exhausted to atmosphere through pipe 30 that the pressure falls in line 32 and pressure switch 31 opens. When solenoids 26 and 23 are energized, lines 16 and 23 are connected with high pressure line 17 and when the solenoids are deenergized, then lines 16 and 23 are cut off from high pressure line 17 and exhausted to atmosphere. Since the pan is jerked quickly from under the load for a distance equal to the length of the stroke of piston 4 and is then slid slowly forward carrying with it the load, the result is that the load has moved along the conveyor pan in the direction of flow a distance somewhat less than the length of the stroke of piston 4. The stroke of piston 4 can, of course, be varied. The time required for the work to pass the full length of the conveyor pan is controlled directly by the number of cycles operated per minute. The timing is controlled by the repeating time delay relay 33 which is adjustable to vary the number of cycles per minute.

If desired pistons 4 and 7 can each be returned slowly to their initial or starting position by means of springs 60, 61 which are either compressed as piston 7 moves in a direction to break the toggle and as piston 4 moves to the left or in counter direction to the flow of the work. If springs are used for returning pistons 4 and 7 to their initial position, then low pressure line 21, chamber 20 and lines 19 and 24 will be omitted.

I claim:

1. A conveyor comprising in combination a pan upon which the work is placed and along which the work is conveyed, means for moving said pan forwardly in the direction which the work is being conveyed at a relatively slow speed so that the work moves with the conveyor, means for releasably latching said pan in its forward position, means in which fluid pressure is built up after the pan completes each forward stroke, control means actuated after said fluid pressure is built up to suddenly release said fluid pressure, means actuated by said released fluid pressure for moving said pan in the opposite direction at a relatively faster speed sufficient to jerk the pan from under the work whereby for each cycle of operation comprising a forward and reverse movement of the pan the work is advanced a distance less than the stroke of the pan, said last mentioned means being ineffective to move the pan in the opposite direction while the pan is latched in its forward position and effective to jerk the pan from under the work when the latching means is released.

2. A conveyor comprising in combination a pan upon which the work is placed and along which the work is conveyed, means for moving said pan forwardly in the direction which the work is being conveyed at a relatively slow speed so that the work moves with the conveyor, toggle means for releasably latching said pan in its forward position, means for moving said pan in the opposite direction at a relatively faster speed sufficient to jerk the pan from under the work whereby for each cycle of operation comprising a forward and reverse movement of the pan the work is advanced a distance substantially equal to the stroke of the pan, said last mentioned means being ineffective to move the pan in the opposite direction while the pan is latched in its forward position by said toggle means and effective to jerk the pan from under the work when the latching means is released.

3. The combination as set forth in claim 2 including means for breaking said toggle means to release the pan for rearward movement.

4. A conveyor comprising in combination a pan upon which the work is placed and along which the work is conveyed, means for moving said pan forwardly in the direction which the work is being conveyed at a relatively slow speed so that the work moves with the conveyor, toggle means for releasably latching said pan in its forward position, means for moving said pan in the opposite direction at a relatively faster speed sufficient to jerk the pan from under the work whereby for each cycle of operation comprising a forward and reverse movement of the pan the work is advanced a distance slightly less than the stroke of the pan, said last mentioned means being ineffective to move the pan in the opposite direction while the pan is latched in its forward position by said toggle means and effective to jerk the pan from under the work when the latching means is released, and means for breaking said toggle means to release the pan for rearward movement, and timing mechanism for controlling the cycle of operation of said toggle breaking means so that the toggle is broken and the pan retracted at predetermined intervals of time.

5. A conveyor comprising in combination a pan upon which the work is placed and along which the work is conveyed, fluid pressure actuated means for moving said pan forwardly in the direction which the work is being conveyed

at a relatively slow speed so that the work moves with the conveyor, means in which fluid pressure is built up after the pan completes each forward stroke, control means actuated after said fluid pressure is built up to suddenly release said fluid pressure, and means actuated by said suddenly released fluid pressure for moving said pan in the opposite direction at a relatively faster speed sufficient to jerk the pan from under the work whereby for each cycle of operation comprising a forward and reverse movement of the pan the work is advanced a distance substantially equal to the stroke of the pan.

6. A conveyor comprising in combination a pan upon which the work is placed and along which the work is conveyed, fluid pressure actuated means for moving said pan forwardly in the direction which the work is being conveyed at a relatively slow speed so that the work moves with the conveyor, means for releasably latching said pan in its forward position, means in which fluid pressure is built up after the pan completes each forward stroke, control means actuated after said fluid pressure is built up to suddenly release said fluid pressure, fluid pressure actuated means for moving said pan in the opposite direction at a relatively faster speed sufficient to jerk the pan from under the work whereby for each cycle of operation comprising a forward and reverse movement of the pan the work is advanced a distance substantially equal to the stroke of the pan, said last mentioned means being ineffective to move the pan in the opposite direction while the pan is latched in its forward position and effective to jerk the pan from under the work when the latching means is released.

7. A conveyor comprising in combination a pan upon which the work is placed and along which the work is conveyed, fluid pressure actuated means for moving said pan forwardly in the direction which the work is being conveyed at a relatively slow speed so that the work moves with the conveyor, a toggle for releasably latching said pan in its forward position, means for storing fluid under pressure, means for breaking said toggle to thereby release said pan for rearward movement, and fluid pressure actuated means for moving said pan in the opposite direction at a relatively faster speed sufficient to jerk the pan from under the work whereby for each cycle of operation comprising a forward and reverse movement of the pan the work is advanced a distance substantially equal to the stroke of the pan, said last mentioned means being ineffective to move the pan in the opposite direction while the pan is latched in its forward position and suddenly effective upon release of said fluid under pressure to jerk the pan from under the work when the toggle is released.

8. The combination as set forth in claim 7 including another fluid pressure actuated means for breaking said toggle, and timing mechanism for controlling the operation of the last mentioned fluid pressure actuated means so that the toggle is broken and the pan retracted at predetermined intervals of time.

9. The combination as set forth in claim 7 including another fluid pressure actuated means for breaking said toggle, and electromagnetically controlled valve mechanism for admitting fluid under pressure to the means for moving the pan in a direction opposite to the flow of the work to build up the fluid pressure in said means before fluid under pressure is admitted to said second

fluid pressure actuated means which breaks said toggle.

10. A conveyor comprising in combination a pan upon which the work is placed and along which the work is conveyed, a cylinder, a piston in said cylinder operatively connected to said pan, means for latching said piston in its forward position, valve controlled means for admitting fluid under pressure into said cylinder on one side of said piston after the pan completes each forward stroke in the direction the work is being conveyed, means for releasing said latching means as soon as the fluid in said cylinder reaches a given pressure whereby the fluid under pressure acts on said piston to move said pan rapidly in a direction opposite to the flow of the work and at such speed that the work remains stationary, and means for admitting fluid under a relatively lower pressure into said cylinder on the opposite side of said piston for moving the piston and pan forwardly in the direction of flow of the work at a relatively slower speed to their starting position so that the work moves with the pan.

11. A conveyor comprising in combination a pan upon which the work is placed and along which the work is conveyed, a cylinder, a piston in said cylinder operatively connected to said pan, means for latching said piston in its forward position, valve controlled means for admitting fluid under pressure into said cylinder on one side of said piston preparatory to releasing said latching means and moving said pan rapidly in a direction opposite to the flow of the work, means for admitting fluid under a relatively lower pressure into said cylinder on the opposite side of said piston for moving the piston and pan forwardly in the direction of flow of the work at a relatively slower speed to their starting position, and a second cylinder and piston having operative connection with the said latching means, and a second valve controlled means for admitting fluid under pressure to said second cylinder after fluid under pressure has been admitted to said first mentioned cylinder whereby the latching means is released.

12. The combination as set forth in claim 11 wherein the latching means is a toggle lever which when in made position holds said piston in its forward position and which when broken releases the piston so that it can jerk the pan rearwardly at a rate of speed sufficient so that the inertia of the load overcomes the friction between the load and the pan.

13. A conveyor comprising in combination a pan upon which the work is placed and along which the work is conveyed, a cylinder, a piston in said cylinder operatively connected to said pan, means for latching said piston in its forward position, a pipe line for admitting fluid under pressure into said cylinder on one side of said piston, a second cylinder, a piston in said second cylinder having an operative connection with said latching means, a second pipe line for admitting fluid under pressure to said second cylinder on one side of said piston and an electromagnetically controlled valve for each of said pipe lines for controlling the flow of fluid under pressure therethrough, an electrical circuit for each of said electromagnetically controlled valves, a pressure controlled switch in the electrical circuit for the electromagnetically controlled valve for the second pipe line, said switch being closed when a predetermined pressure is reached in the first cylinder whereby when the one electrical circuit is closed the electromagnetically con-

trolled valve for the first pipe line opens to admit fluid under pressure to the first cylinder and upon a predetermined rise in pressure in the first cylinder the pressure switch closes to close the second circuit and open the second valve to admit fluid under pressure to the second cylinder and thereby release the latching means whereupon the fluid under pressure in the first cylinder moves the conveyor pan back from under the work at a relatively fast speed, and means for returning the pan to its initial position at a relatively slow speed and for resetting said latch.

14. A conveyor comprising in combination a pan upon which the work is placed and along which the work is conveyed, a cylinder, a piston in said cylinder operatively connected to said pan, means for latching said piston in its forward position, a pipe line for admitting fluid under pressure into said cylinder on one side of said piston, a second cylinder, a piston in said second cylinder having an operative connection with said latching means, a second pipe line for admitting fluid under pressure to said second cylinder on one side of said piston and an electromagnetically controlled valve for each of said pipe lines for controlling the flow of fluid under pressure therethrough, an electrical circuit for each of said electromagnetically controlled valves, a pressure controlled switch in the electrical circuit for the electromagnetically controlled valve for the second pipe line, said switch being closed when a predetermined pressure is reached in the first cylinder whereby when the one electrical circuit is closed the electromagnetically controlled valve for the first pipe line opens to admit fluid under pressure to the first cylinder and upon a predetermined rise in pressure in the first cylinder the pressure switch closes to close the second circuit and open the second valve to admit fluid under pressure to the second cylinder and thereby release the latching means whereupon the fluid under pressure in the first cylinder moves the conveyor pan back from under the work at a relatively fast speed, a source of fluid under a relatively low pressure connected to said cylinders on the opposite sides of said pistons whereby the fluid under low pressure returns the pistons to their initial position at a relatively slow speed thereby moving the pan slowly in the direction of flow and resetting said latching means.

15. The combination as set forth in claim 14 including a limit switch for breaking the circuit to the electromagnetically controlled valves before the pan reaches the end of its rearward stroke whereby the fluid under high pressure is exhausted from the cylinders and the fluid under low pressure returns the pistons to their starting position.

16. The combination as set forth in claim 14 including a limit switch for breaking the circuit to the electromagnetically controlled valves before the pan reaches the end of its rearward stroke whereby the fluid under high pressure is exhausted from the cylinders and the fluid under low pressure returns the pistons to their starting position, and a timing switch in the circuit for the electromagnetically controlled valves arranged to close this circuit at predetermined intervals of time.

17. A conveyor comprising in combination a pan upon which the work is placed and along which the work is conveyed, a cylinder, a piston in said cylinder operatively connected to said

pan, means for latching said piston in its forward position, a pipe line for admitting fluid under pressure into said cylinder on one side of said piston, a second cylinder, a piston in said second cylinder having an operative connection with said latching means, a second pipe line for admitting fluid under pressure to said second cylinder on one side of said piston and an electromagnetically controlled valve for each of said pipe lines for controlling the flow of fluid under pressure therethrough, an electrical circuit for each of said electromagnetically controlled valves, a pressure controlled switch in the electrical circuit for the electromagnetically controlled valve for the second pipe line, said switch being closed when a predetermined pressure is reached in the first cylinder whereby when the one electrical circuit is closed the electromagnetically controlled valve for the first pipe line opens to admit fluid under pressure to the first cylinder and upon a predetermined rise in pressure in the first cylinder the pressure switch closes to close the second circuit and open the second valve to admit fluid under pressure to the second cylinder and thereby release the latching means whereupon the fluid under pressure in the first cylinder moves the conveyor pan back from under the work at a relatively fast speed, resilient means connected to said pistons for returning the pistons to their initial position at a relatively slow speed thereby moving the pan slowly in the direction of flow and resetting said latching means.

18. A conveyor comprising in combination a pan upon which the work is placed and along which the work is conveyed, means for moving said pan forwardly in the direction which the work is being conveyed at a relatively slow speed so that the work moves with the conveyor, toggle means for releasably latching said pan in its forward position, a source of potential energy, means actuated by said potential energy when the toggle means is released for moving said pan in the opposite direction at a relatively faster speed sufficient to jerk the pan from under the work whereby for each cycle of operation comprising a forward and reverse movement of the pan the work is advanced a distance slightly less than the stroke of the pan, said last mentioned means being ineffective to move the pan in the opposite direction while the pan is latched in its forward position by said toggle means and effective to jerk the pan from under the work when the toggle means is released, control means actuated after the pan completes each stroke, and means for breaking said toggle means whereby said potential energy is suddenly released and the pan also released for quick rearward movement.

19. A conveyor comprising in combination a pan upon which the work is placed and along which the work is conveyed, means for moving said pan forwardly in the direction which the work is being conveyed at a relatively slow speed so that the work moves with the conveyor, a toggle for releasably latching said pan in its forward position, means in which fluid pressure is built up after the pan completes each forward stroke and is latched in such position by said toggle, control means actuated to release said toggle means after said fluid pressure is built up whereby said fluid pressure is released, means actuated by said fluid pressure as soon as said toggle is released for moving said pan in the opposite direction at a relatively faster speed sufficient to jerk the pan from under the work where-

by for each cycle of operation comprising a forward and reverse movement of the pan the work is advanced a distance slightly less than the stroke of the pan, said last mentioned means being ineffective to move the pan in the opposite direction while the pan is latched in its forward position by said toggle means and effective to jerk the pan from under the work when the toggle means is released.
